PATCH WEAVING DEVICE

William Abbott, Hollywood, Calif.

Application May 20, 1949, Serial No. 94,485

1 Claim. (Cl. 139—1)

1

This invention relates to new and useful improvements and structural refinements in devices used for interweaving a patch over a damaged area in fabric material, and the principal object of the invention is to perform the patch weaving or securing operation with great speed, convenience and without labor demanding special skill.

In particular, the invention concerns itself with so-called "invisible mending," whereby a patch of the same material as the fabric which is to be mended is applied to the damaged area and loose threads at the marginal edges of the patch are drawn through the interwoven threads of the material under repair, so that when the operation is completed, the presence of the patch cannot be readily detected.

Various different methods have been proposed in the past for installing the patch, but all such methods involve the drawing of the loose threads of the patch through the interwoven threads of the material under repair, and since this thread drawing operation is obviously a difficult and a delicate task, the invisible mending procedure calls for skilled labor and is, therefore, quite expensive. The instant invention seeks to eliminate these disadvantages by providing an instrument whereby the threads of the patch may be quickly and easily drawn or inserted through the threads of the material under repair, so that the installation of the patch may be quickly and easily effected even by persons of limited skill, as aforesaid.

The object of the invention is carried out by the provision of an instrument including a pair of juxtaposed needles which are resiliently connected for movement toward and away from each other, so that they are well adapted to clamp a loose thread of the patch therebetween and to draw or pass the loose thread through the material under repair.

Needless to say, the needles employed in the instrument are made with utmost precision, and therefore, an important feature of the invention resides in the provision of means in the instrument for supporting and manipulating the needles, this feature eliminating the necessity of machining at substantial expense parts which are large enough to be manipulated by hand.

Another feature of the invention resides in the structure of the needles themselves, particularly in the structural features of these needles which enable them to firmly and securely grasp or clamp a loose thread of the patch.

Some of the advantages of the invention lie in its simplicity of construction, in its pleasing ap-

pearance, and in its adaptability to economical manufacture.

With the above more important objects and features in view, and such other objects and features as may become apparent as this specification proceeds, the invention consists essentially of the arrangement and construction of parts as illustrated in the accompanying drawings, in which:

10 Figure 1 is a perspective view showing the invention in use;

Figure 2 is a longitudinal cross-sectional view of the invention per se;

15 Figure 3 is a cross-sectional detail, taken substantially in the plane of the line 3—3 in Figure 2;

Figure 4 is a fragmentary side elevational view of one of the needles used in the invention;

20 Figure 5 is a fragmentary elevational view, taken substantially in the plane of the line 5—5 in Figure 4;

Figure 6 is a cross-sectional detail, taken substantially in the plane of the line 6—6 in Figure 4;

25 Figure 7 is a fragmentary side elevational view of the second needle used in the invention;

Figure 8 is a fragmentary elevational view, taken substantially in the plane of the line 8—8 in Figure 7;

Figure 9 is a cross-sectional detail, taken substantially in the plane of the line 9—9 in Figure 7; and

30 Figure 10 is a plan view of a patch with which the invention is intended to be used.

Like characters of reference are employed to designate like parts in the specification and throughout the several views.

Referring now to the accompanying drawings in detail, the invention consists of a patch weaving device or instrument designated generally by the reference character 20, the same embodying in its construction a substantially tubular casing 12 having an open end and a closed end 14, the open end of the casing being provided with a tubular adapter 16 which has a diametrically reduced portion 18 pressed in the open end of the casing, as is best shown in Figure 2.

The adapter 16 is also provided with an outward extension having a tapered outer surface 20, the purpose of which will be hereinafter more fully described.

What may be referred to as a needle support designated generally by the reference character 22 is positioned in the casing 12 and consists of a pair of juxtaposed arms 24, 26 of resilient material, which are connected together at one end

thereof, that is, adjacent the closed end 14 of the casing 12, as indicated at 28.

The free end portions 30, 32 of the respective arms 24, 26 are disposed in the adapter 16 and, by virtue of the resiliency thereof, are movable toward and away from each other, and a pair of juxtaposed needles 34, 36 are secured by welding, or the like, to the respective arm portions 30, 32, as illustrated in Figure 2.

The needles 34, 36 project outwardly from the adapter 16 of the casing 12 and it is to be noted that the inner end portions of the needles which are secured to the arms 24, 26 are substantially semi-cylindrical in cross-section, as is best shown in Figure 3.

Intermediate portions of the needles, on the other hand, assume the form of shanks having flat sides 38, 40, respectively, while the respective needles 34, 36 are provided at the outer ends thereof with enlarged heads 42, 44 terminating in pointed extremities 46, 48, respectively.

It is to be noted that the needle 36 is provided in the head end portion thereof with a longitudinally extending channel 50 having a flat bottom 52, this channel being adapted to receive the head end portion of the needle 34 having a flat bottom 54 which is engageable with the flat bottom 52 of the channel 50 when the needle 34 is pressed against the needle 36, as indicated by the dotted lines 56 in Figure 2.

Means are provided for pressing the two needles together, these means consisting of a limb 58 which is anchored as at 60 to the side wall of the casing 12 and has an angulated end portion 62 which projects inwardly through registering apertures provided in the casing and in the adapter 16, as indicated at 64. The inner end of the end portion 62 bears against the aforementioned arm 24, and it will be readily apparent that by simply depressing the limb 58 against the casing 12, the arm 24 will be pressed toward the arm 26 and the head portions of the needles 34, 36 will be brought together, as aforesaid.

A guide member 66 is pressed in the outer end portion of the adapter 16 and is provided with a slot 68 through which the needles 34, 36 extend, so that the needle 34 is effectively guided in its movement toward and away from the needle 36, as will be clearly apparent.

Finally, it is to be observed that a cap 70, having a tapered open end portion 72, is removably receivable on the tapered outer surface 20 of the adapter 16, so as to protect the needles 34, 36 when the invention is not in use.

The invention is, of course, intended for use in installing a patch 74 on a damaged area 76 in fabric material 78, the patch 74 being of the conventional type and including at its marginal edge a plurality of loose threads 80, as shown in Figure 10.

The invention is intended for pushing the loose threads 80 of the patch 74 through the interwoven threads of the material 78, this being accomplished by simply manipulating the instrument while its needles are separated so that one of the loose threads is disposed in the channel 50 of the needle 36, and thereafter depressing the limb

58 so that the needle 34 is brought toward the needle 36 and the loose thread is tightly clamped between the surfaces 52, 54 of the two needles. The two needles together with the loose thread 5 may then be pushed through the interwoven threads of the fabric 78, after which pressure on the limb 58 is relaxed so that the needles are permitted to spread apart, thus facilitating a 10 release of the loose thread from the needles and permitting the needles to be withdrawn while the loose threads remain extended through the fabric 78. Needless to say, the same procedure is 15 repeated until all the loose threads of the patch 74 are projected through the fabric 78, after which 20 the loose threads are secured by stitching on the reverse side of the fabric to complete the mending operation. If desired, the patch 74 may be basted to the material 78 as indicated at 82 before the mending operation is undertaken, so that the 25 patch does not shift from its proper location while the loose threads thereof are being drawn through the material under repair.

It is believed that the advantages and use of the invention will be clearly apparent from the 25 foregoing disclosure and, accordingly, further description thereof at this point is deemed unnecessary.

While in the foregoing there has been shown and described the preferred embodiment of this 30 invention it is to be understood that minor changes in the details of construction, combination and arrangement of parts may be resorted to without departing from the spirit and scope of the invention as claimed.

35 Having described the invention, what is claimed as new is:

In a patch weaving device, a substantially tubular casing, a resilient needle support positioned in said casing and including a pair of juxtaposed 40 arms connected together at one end and having free end portions movable toward and away from each other, a pair of needles secured to the free end portions of the respective arms and projecting outwardly from said casing, said casing having 45 a side wall provided with an opening, and actuating means comprising a depressible limb attached at one end thereof to said casing, the other end of said limb being provided with an angulated portion extending through said opening into the casing and operatively engaging one of said arms 50 whereby said needles may be pressed together to clamp a thread therebetween.

WILLIAM ABBOTT.
